UNITED STATES PATENT OFFICE.

CHARLES B. GOES, OF CHICAGO, ILLINOIS.

DISPLAY CARD.

Application filed February 23, 1922. Serial No. 538,632.

To all whom it may concern:

Be it known that I, CHARLES B. GOES, a citizen of the United States, residing at Chicago, in the county of Cook and State of Illinois, have invented certain new and useful Improvements in Display Cards, of which the following is a specification, reference being had to the accompanying drawings and to the reference characters marked thereon, which form a part of this specification.

This invention relates to display cards, or display easels as they are sometimes called designed for use for advertising purposes, and more particularly to the knock-down type which when folded for use are adapted to stand in a vertical position with or without a self-contained brace or easel.

The invention consists in the novel devices and combination of devices herein illustrated, described and more particularly pointed out in the appended claims.

In the drawings:

Fig. 1 is a side elevation of a device embodying my invention, fully assembled and standing in an erect position.

Fig. 2 is a transverse, horizontal, sectional view, taken upon the dotted line 2—2 of Fig. 1, looking in the direction indicated by the arrows.

Fig. 3 is a rear elevation of the device.

Figs. 4 and 5 are plan views of the two interlocking side members.

Fig. 6 is a sectional view of a detail showing a modified form of securing the back members to the front member.

In the drawing, A represents a sheet, preferably of cardboard, generally rectangular in form and having a length considerably in excess of its width. Its lower edge 1 is, preferably, straight so as to form a base for the support of the device. Its side margins may be given any desired contour or configuration, as for instance that shown at 2. It is understood of course that this part A may be of any size and shape, depending on the use to which it is to be put.

To this board A are secured two side members B and C. The side member B, shown in Fig. 5, is substantially rectangular in shape and is provided along one of its longitudinal margins with an attaching flap 3 adapted to be secured by any suitable means, as for instance mucilage, to the inside surface of one margin of the front member A,

as clearly shown in Fig. 2. The other side member C has a similar flap 4 adapted to be secured to the inside surface of the other margin of the front member A. The flaps 3 and 4 are made flexible with respect to the member B and C by scored or weakened lines 5 and 6 respectively.

From the other side margin 7 of the member B there projects a tongue 8, joined to the member B by a narrow section 9, leaving recesses 10, 10, on both sides of the tongue 8 adjacent to the side edge 7. Through the member C is an aperture or opening 11 of a shape adapted to receive the tongue 8. In opposite corners of the opening 11 are recesses 12, 12, the distance between the recesses being approximately equal to the width of the tongue 8. The distance between the inner margins of the recesses 10, 10, of the member B is approximately equal to the width of the opening or aperture 11. Thus when the two parts B and C are brought together as shown in Fig. 3, the tongue 8 is passed through the opening 11 along the line 13 until the recess 10 of the member B is opposite the recess 12 of the member C, whereupon the side portions 14 of the tongue 8 are moved so as to be superposed upon the side portions 15 of the member C and then the two members B and C may be moved laterally until they are in the interlocked position shown in Fig. 3. In order to move the members B and C into this locked position, it will first be necessary to bend the front member A into the curved form as shown in Figs. 1 and 2. This is readily accomplished for it will be understood that the distance between the points of attachment of the two back members B and C to the front member A, when the latter lies flat, is greater than when the front member A is bent, and is greater than the width of the back as a whole when its two members B and C are in interlocked position.

When unfolded and ready to be packed for shipment, the members B and C are preferably laid flat against the inside of the front member A. It may also be convenient to fold the front member A, particularly when said member is of considerable length or height. Such folding may take place upon the scored or weakened line 16. It will be found in use that this folding of the member A upon the line 16 for convenience in shipping will not interfere with

the part A standing in an erect position when the device is assembled, due to the flexing of the member A as a whole, as shown in Figs. 1 and 2.

5 In many instances, the easel or display card just described will stand in an erect position, resting upon the lower edge 1 of the front member and the lower edges 17 and 18 of the members B and C which together form the back. It may, however, be desirable to further support the display card and this I accomplish by means of an easel or brace member D. The member D is formed out of the member C by cutting along the lines 19, 20 and 21 and by scoring along the diagonal line 22 which runs from the base of the line 20 to the line 21, and scoring also along the vertical lines 23, 24.

Assuming that the parts B and C are interlocked as more clearly shown in Figs. 2 and 3, the easel or brace member D is then bent along the scored lines 23 and 24 until it stands substantially at a right angle to the surface of the member C, as shown in Figs. 1 and 2. In order to more securely hold or lock the easel or brace member D in this position, a locking flap E is bent upon the horizontally scored line 25 until the notch 26 in its upper edge engages the inside edge 21^a of the aperture formed in the easel D by the cut line 21. This will be clearly understood by reference to Figs. 1 to 4, inclusive. The object of cutting along the diagonal line 20 and of scoring along the line 25 is to permit this locking flap E to be bent over into a horizontal position for the purpose of engaging and locking the member D. It will be understood of course that where the device is of such a nature as to readily stand on the base lines 1, 17 and 18, the card may be simplified in construction and cost of manufacture by omitting the cutting along the lines 19, 20 and 21 and the scoring of the parts necessary to form the flaps D and E.

55 In some instances, the nature of the cardboard used may be such as to produce undue wear along the scored line 6. This may be avoided by reversing the position of the flap 4 and attach it to the front member A in the modified form as shown in Fig. 6. In this modification, the flap 4 is bent toward the back instead of being bent toward the front as in the form first described.

It will be understood that the supporting member D need not in all cases be used. The size of the device and the curve given to the front member A may be sufficient to produce a base.

60 I claim as my invention:

1. A display card of the class described, comprising a front member, a back consisting of two separate members, said back members each having a marginal flap by which they are secured to opposite rear mar-

gins of the front member, and interlocking means on the two back members whereby when interlocked the front member is caused to assume a curved position, said interlocking means comprising a notched aperture on one back member and a notched tongue on the other. 70

2. A display card of the class described, comprising a front member, a back consisting of two separate members, said back members each having a marginal flap by which they are secured to opposite rear margins of the front member, and interlocking means on the two back members whereby when interlocked the front member is caused to 75 assume a curved position, said interlocking means comprising a notched aperture in one back member and a notched tongue projecting from the free margin of the other back member. 80

3. In a display card of the class described, a front member, two back members secured to opposite margins of the same side of the front member, interlocking means on the back members and a brace member formed 90 in one of the back members and adapted to be folded at an angle thereto, and means on the back member for locking said brace member in its folded angular position.

4. In a display card of the class described, 95 a front member and two back members each secured along one of its margins to the front member and means for interlocking the free margins of the back members, one of said back members being cut and scored to include a brace member adapted to be folded at an angle to the surface of said back member, the cut line extended horizontally in from the free margin to define the top of the brace and the scored line extending vertically from the inner end of said cut line. 100

5. In a display card of the class described, 105 a front member, a back comprising two separate back members, each secured along one of its margins to the front member, and means for interlocking the free margins of the contacting members, one of said back members being cut on a horizontal line and scored on a vertical line to include a brace member which when folded along the 115 severed line, will stand at an angle to the surface of said back member, and a lug cut from the same back member and its brace member and adapted to be folded on a scored line to engage and lock the brace member. 120

6. In a display card of the class described, 125 a front member, a back composed of two separate members, said back members being each provided with a marginal flap by which they may be secured to opposite rear margins of the front member, longitudinal scoring between each back member and its flap, a notched aperture in one back member and a notched tongue projecting from the free margin of the other back member, and 130

adapted to engage said aperture, whereby the two back members may be brought into interlocked relation.

7. In a display card of the class described, 5 a front member, two back members each provided with a marginal flap by which it may be secured to the front member, scoring between each back member and its flap, a 10 notched tongue projecting from the free margin of the other back member and adapted to engage the said aperture whereby

the two back members are brought into interlocking relation, and an easel member formed in one of the back members adapted 15 to be folded in angular relation thereto.

In testimony that I claim the foregoing as my invention I affix my signature, in the presence of two witnesses, this 16th day of February, 1922.

CHARLES B. GOES.
